Attorney

UNITED STATES PATENT OFFICE.

FRED A. HOMEWOOD, OF GLENDO, WYOMING.

GRAVITY SEPARATOR.

Application filed October 15, 1925. Serial No. 62,597.

To all whom it may concern:

Be it known that I, FRED A. HOMEWOOD, a citizen of the United States, residing at Glendo, in the county of Platte and State 5 of Wyoming, have invented certain new and useful Improvements in Gravity Separators, of which the following is a specification, reference being had to the accompanying drawings.

10 This invention relates to gravity separators and more particularly to a device of this character adapted for the separation of metals from ores.

An important object of the invention is to 15 provide a device of this character employing siphons as a means for effecting separation.

A further object of the invention is to 20 provide a device of this character which may be very cheaply and readily produced and which may be very cheaply operated.

A still further object of the invention is to 25 provide a device of this character in which the separation is substantially automatic.

These and other objects I attain by the 30 construction shown in the accompanying drawings, wherein for the purpose of illustration is shown a preferred embodiment of my invention and wherein:—

Figure 1 is a side elevation showing a 35 gravity separator constructed in accordance with my invention;

Figure 2 is a vertical sectional view 40 through a unit of the separator;

Figure 3 is a perspective of the lower 45 end of the intake leg of the silt removing siphon.

Referring now more particularly to the 50 drawings, the numeral 10 designates a tank into which extends an ore feed pipe 11, the inner end of which is arranged adjacent the bottom of the tank, as indicated at 12. This ore feed pipe has preferably attached 55 to the lower end thereof a pan 13 for receiving mercury for the collection of values from the ore as it impinges thereagainst during the passage of the ore into the tank. The tank has likewise communicating there- 60 with a water inlet pipe 14, the purpose of which will presently appear.

In combination with such a tank, I pro- 65 vide a pair of siphons 15 and 16, the former being hereinafter referred to as a silt siphon 70 and the latter as a values siphon. The

silt siphon has its short leg 17 arranged within the tank and its bight portion 18 extending through the wall of the tank. The bight portion and short leg of this siphon are both of greater diameter than the 60 long or discharge leg 19 thereof and the intake or short leg is subdivided by a diametrically extending flange 20 continuing from the lower end of the leg through the adjacent portion of the bight of the leg, 65 this flange serving to prevent swirling of the contents of the leg so that eddy currents are not set up which will pick up values for delivery to the leg 19. The leg 17 and bight portion being of greater diameter than the 70 leg 19, the rate of flow through the leg 17 is relatively slow which further assists in the prevention of picking up of these values by the siphon. The lower end of the leg 17 is well spaced from the bottom 21 of the tank. 75

The construction of the values siphon is reversed; the intake leg 22 thereof being relatively small while the bight portion 23 and exhaust leg 24 are relatively large. In the exhaust leg, a diametrical partition 25 is arranged, the upper end of which projects upwardly above the level of the lower surface of the bight 23, for a purpose presently to appear. The lower end of this partition projects below the lower end of the siphon and has secured thereto a discharge pan 26 for the reception of mercury and having compartments 26^a and 26^b into which the contents of the leg 24 at opposite sides of the partition 25 are directed. These pans discharge into the compartments 27 and 28 of a tank 29. The compartment 28 has an outlet 30 which may form the ore feed pipe for a second tank 10^a similar to the tank 10. The values discharge siphon 16^a of this tank 10^a may discharge into a second tank 29^a similar to the tank 29. This cascading of values may be continued as long as it is found desirable or necessary. The compartment 27 is provided with a suitable outlet 32. 85

In the operation of the device, the ore is fed into the tank until the same is substantially filled with the ore and water and the same has partially separated. The siphons 15 and 16 are then started in operation and the siphon 15 will draw off water and the lighter particles of the ore, such as mud, finely divided rock and light sand. Since this siphon will have a tendency to 100

draw off a certain percentage of float gold, the bight of the siphon may be provided with a pocket 31 for the reception of this float gold. The values are drawn off by the siphons 16 and due to the fact that when the contents of the leg 22 arrive at the bight 23 the size of this siphon increases, the rate of flow through this bight portion will be relatively slow and will permit the heavier portions of the values to drop to the bottom wall of the bight so that as they pass to the leg 24, they will lie at that side of the partition 25 next adjacent the bight and will be discharged into the pan section 26^b and finally into the compartment 28 of the tank 29 unless they amalgamate in the pan. The lighter values will pass to the pan section 26^a and finally to the tank section 27. It will be obvious that by repeating this process, as indicated by the discharge of the tank 29 into a second apparatus of this character, a very fine separation may be effected.

It will also be obvious that the construction hereinbefore set forth is obviously capable of a certain range of change and modification without materially departing from the spirit of the invention, and I accordingly do not limit myself to such specific structure except as hereinafter claimed.

I claim:

1. In a separator of the type described, an ore tank, a pair of siphons communicating with said tank having their intake legs arranged within the tank and one having the lower end of its intake leg arranged adjacent the bottom of the tank while the second has its intake leg spaced therefrom and means in the discharge leg of the first named siphon for gravity separation of values passing therethrough.
2. In a separator of the type described, an ore tank, a pair of siphons communicating with said tank having their intake legs arranged within the tank and one having the lower end of its intake leg arranged adjacent the bottom of the tank while the second has its intake leg spaced therefrom, the

first named siphon having a relatively small intake leg and large exhaust leg, the last 50 named siphon having a relatively small exhaust leg and a relatively large intake leg.

3. In a separator of the type described, an ore tank, a pair of siphons communicating with said tank having their intake legs arranged within the tank and one having the lower end of its intake leg arranged adjacent the bottom of the tank while the second has its intake leg spaced therefrom, the first named siphon having a relatively 55 small intake leg and large exhaust leg, the last named siphon having a relatively small exhaust leg and a relatively large intake leg and means in the discharge leg of the first named siphon for gravity separation of 60 values passing therethrough.

4. In a separator of the type described, an ore tank, a pair of siphons communicating with said tank having their intake legs arranged within the tank and one having the lower end of its intake leg arranged adjacent the bottom of the tank while the second has its intake leg spaced therefrom, 70 and a diametrically extending partition within the exhaust leg of the first named 75 siphon having its upper ends projected above the level of the lower surface of the bight of the siphon.

5. In a separator of the type described, an ore tank, a pair of siphons communicating with said tank having their intake legs arranged within the tank and one having the lower end of its intake leg arranged adjacent the bottom of the tank while the second has its intake leg spaced therefrom, 80 a diametrically extending partition within the exhaust leg of the first named siphon having its upper ends projected above the level of the lower surface of the bight of the siphon and separate tanks for receiving 85 the discharges at the opposite sides of the partition of said exhaust leg.

In testimony whereof I hereunto affix my signature.

FRED A. HOMEWOOD.
